TAP WRENCH

Karl A. Kuhn, Greenfield, Mass., assignor to
Greenfield Tap and Die Corporation, Green-
field, Mass., a corporation of Massachusetts

Application June 21, 1937, Serial No. 149,425

1 Claim. (Cl. 10—149)

This invention relates to wrenches and particularly to an adjustable wrench for taps, reamers and the like.

A main object of the invention is to provide 5 a wrench of the indicated type that has fewer parts and is more compact without sacrificing strength. Another purpose is to provide a construction that may be readily manufactured, being adapted for production by an automatic machine from bar steel.

Other objects and advantages will appear from the following description taken in connection with the accompanying drawing, in which

Fig. 1 is a plan face view of the wrench;

15 Fig. 2 is a similar edgewise view;

Fig. 3 is a view similar to Fig. 1 showing the body, jaw and associated parts in central longitudinal section;

20 Fig. 4 is a transverse section on line 4—4 of Fig. 1, and

Fig. 5 is a transverse section on line 5—5 of Fig. 2.

The wrench comprises an integral body 11 having tapered end portions 12 and intermediate side portions 13 formed concentric with the longitudinal axis of the body 11, the end and side portions preferably being formed substantially on an arc of a circle in longitudinal section as shown in Fig. 3. Opposite faces 14 intermediate sides 13 and ends 12 include a relatively flat central portion and outwardly curved end zones adjacent the end portions 12 to provide increased thickness of metal at these points.

A transverse opening 15 extends through the 35 body 11 between faces 14 and is provided at one end with gripping faces 16 at right angles to each other, with parallel side walls 17 serving as jaw guides. Jaw 18 is slidably mounted between walls 17 and provided with a gripping face in the form of a right angled notch 19 aligned with the angle between faces 16 to grip opposite angles of a squared shank.

A bar handle 20 is threaded in bore 21 in body 11 by a right hand thread, and a pin 22 is threaded in bore 23 in the end of handle 20 by a left hand thread. The outer end of pin 22 engages jaw 18, as by a press fit in a suitable bore 24 in said jaw. A cooperating fixed bar handle 25 is mounted on the opposite end of body 11 in alignment with handle 20, as by screwing the end of handle 25 tightly into bore 26 in said body.

The parts are arranged so that a reverse rotation of handle 20 will retract the handle in bore 21 and simultaneously retract pin 22 in bore 23 in the handle, rapidly withdrawing the jaw 18 until it reaches the end of the opening 15, the parts being proportioned so that in this position

5 handle 20 will have a sufficiently extensive bearing surface against the body 11 to provide the necessary strength to withstand the heavy strains to which the device may be subjected in use. To increase this bearing surface the gripping faces 16 may be located somewhat beyond the longitudinal center of the body 11.

To engage the shank of a tap, reamer or other tool after jaw 18 has been fully retracted, clockwise rotation of handle 20 will force jaw 18 toward the gripping faces 16 to engage such shank rapidly and solidly, the double screw arrangement providing ready engagement and disengagement as well as firm gripping action. The thickened portions of the body adjacent the intersections of faces 14 and end portions 12 overlie bores 21 and 26.

10 The construction provides a compact, neat, and strong body free from projections and which 20 provides the requisite strength at all points of strain. The body is suitably contoured for ready manufacture from bar steel on an automatic machine, and may be made by standard processes 25 from steel of the necessary strength and hardness, permitting the incorporation of integral gripping faces 16 on the body itself.

While various designs and arrangements are possible, within the scope of the invention as defined in the claim, the preferred embodiment has 30 been illustrated to scale to indicate desirable proportion and relationships between parts.

I claim:

A tap wrench comprising a flat body 11 of 35 bar steel tapering to less width toward each end in the plane of the faces 14 and enlarged in thickness at each end in a direction normal to said faces 14 to form conical end portions 12, said body 11 having a slot 15 with jaw 16 at one end and the threaded bore 21 opening from said slot at the other end, a handle 25 at one end of said body, a jaw 18 sliding in said slot and having a bore 24, a rotatable handle 20 threaded into the bore 21 in one end of said body 11 and having a threaded bore 23 within its threaded end and within the bore 21 of said body and carrying an enlarged grip portion at its outer end, and a pin 22 having at one end a head force-fitted into said bore of said jaw and threaded at the other end into the bore 23 of the rotatable 50 handle 20 so that all of the threaded adjusting means are overlapped within one end of said body 11, said conical end portions 12 being of sufficient size to support the wrench in all positions with the enlarge grip of the rotatable 55 handle 20 entirely out of contact with a flat supporting surface.

KARL A. KUHN.
